UNITED STATES PATENT OFFICE

138,006

DESIGN FOR A TOY WALKER FOR DOLLS

Erwin F. Wittenberg, Milwaukee, Wis.

Application February 5, 1944, Serial No. 112,467

Term of patent 7 years

(Cl. D34—15)

To all whom it may concern:

Be it known that I, Erwin F. Wittenberg, a citizen of the United States and resident of Milwaukee, in the county of Milwaukee and State of Wisconsin, have invented a new, original, and ornamental Design for Toy Walkers for Dolls, of which the following is a specification, reference being had to the accompanying drawing, forming part thereof.

Figure 1 is a front elevational view of the toy walker for dolls showing my new design.

Figure 2 is a top plan view of the toy walker a portion of the tongue being broken away for convenience in the illustration.

Figure 3 is a side elevational view of the toy walker.

I claim:

The ornamental design for a toy walker for dolls, as shown.

ERWIN F. WITTENBERG.
